STATIONARY INDUCTION APPARATUS

Richard F. Kneisley, Toledo, Ohio

Application September 23, 1937, Serial No. 165,379

3 Claims. (Cl. 171—119)

This invention relates to stationary induction apparatus, and is more particularly directed to high reactance, shell type, transformers.

The invention is particularly used in connection with a shell type transformer in which it is desired to introduce additional magnetic circuits so as to increase the internal reactance of the transformer. It is frequently desirable to add magnetic leakage paths between the primary and secondary windings to increase the reactance of the transformer to such a value as will insure its protection from the flow of abnormally high current to short circuits, or other conditions which might increase the flow of an abnormally high value.

The provision of additional magnetic paths necessitates the insertion of laminated stacks of magnetic material between the core and shell of the transformer and between the primary and secondary coils. It has been found in practice that stacks of laminations of this character may be assembled so as to be relatively noiseless for a short period of time, but after the transformer has been in use and becomes heated and cooled through several cycles, these laminations work loose and the magnetic stress to which they are subjected causes them to hum and make the transformer objectionably noisy.

It has also been found that in most transformers, it is necessary to assemble the laminations with some type of fastening means to hold them in place relative to the remaining transformer parts. Fastening elements which pierce the laminations cause eddy currents to be set up therein and increase the operating temperature, at least locally, of the transformer. Further, such fastening elements are relatively expensive if made of proper material and if properly constructed and assembled.

The primary object of the present invention is the provision of a device to provide additional magnetic paths in a transformer, constructed in such a manner that it will remain noiseless throughout its entire life and may be held in place in a transformer preferably without the use of extraneous fastening elements.

Other objects and advantages of the invention will become apparent as the description proceeds, reference being had to the accompanying drawing, in which—

Figure 1 is a plan view of a transformer embodying the present invention; Fig. 2 is a section on line 2—2 of Fig. 1; Fig. 3 is a perspective view, with parts broken away, of a magnetic leak

vention, and Fig. 4 is a view of a modified form of leak unit.

Referring to the drawing, the invention is shown in connection with a transformer having a primary winding 1 and a secondary winding 2 disposed about a center core of laminated magnetic material 3 and within the confines of a built up magnetic shell 4. The laminations of the shell 4 are held in place by upper and lower retaining members 5 and 6 which are fastened together by suitable bolts 8. As in the usual practice, wooden wedges 9 are used to tighten the primary and secondary coils on the core 3.

In a transformer of this type, it is frequently desirable to provide an additional magnetic path which is really a leakage path or shunt since the flux from the primary is permitted to flow without linking a secondary coil. For this purpose, laminations are introduced between the shell 4 and core 3 at a point between the primary and secondary coils.

The leakage, or shunt, paths in accordance with the present invention include units 10 which are made up of stacks of magnetic material in the form of thin laminations 11 which are molded 25 as a unit by completely embedding them in a covering 12 which is preferably of relatively yieldable rubber, or other material having similar characteristics. The magnetic "leak" units 10 may be made in any suitable manner, although 30 a simple method is to place the stack of previously cut laminations 11 in a mold, spaced from the bottom and sides thereof and fill the mold with rubber.

The leak units may be placed in the transformer during the assembly operation, and when the shell 4 is fixed in its final position, it is forced into biting engagement with the leak units which in turn are forced tightly against the core 3. Since the covering of the leak units possesses considerable inherent resiliency, no other fastening elements are required to hold the units in place relative to the shell and core of the transformer. The resiliency of the covering surrounding the leak laminations provides, in addition, a continuous gripping tension, holding the laminations together, and thus dampens the vibrations of the laminations which are caused by the changing magnetic flux. This eliminates noise or hum which such vibrations would otherwise produce.

If desired, the units may be previously formed to a configuration such as shown in Fig. 4 and introduced into the transformer after assembly and held therein by reason of the rubber covering engaging the stacks of laminations which

form the principal magnetic paths in the transformer. In this form the unit may be provided with a head part 12' slightly larger than the remainder of the body. The unit may thus be forced between the core and shell until the head 12' rests on the adjacent metallic parts.

While the invention has been described in connection with a transformer of a particular type and construction, it should be appreciated that 10 it is adaptable to any type transformer in which shunt paths are used to increase the reactance. Such adaptation will undoubtedly require a change in configuration of the leak unit.

Having thus described my invention, what I 15 claim as new, and desire to secure by United States Letters Patent, is:

1. A stationary induction apparatus including a magnetizable shell and a core member therewithin and spaced therefrom, inductively related 20 windings embracing said core, and a magnetizable shunt between said core and shell, said shunt including a body having magnetizable laminations, and a resilient covering, said covering being of a strength and its resilience of a degree where- 25 by to hold the laminations against vibrations, the overall width of said covered shunt being greater than the distance between the core and shell whereby upon compression to hold the shunt firmly in position.

30 2. A stationary induction apparatus including

a magnetizable shell and a core therewithin and spaced therefrom, inductively related windings embracing the core, a magnetizable shunt held between said core and shell to form a leakage path for flux from one of said windings and including a body of magnetic laminations, and a resilient covering for said shunt having a degree of resiliency to exert a constant gripping action on the shunt to hold its laminations against vibration, the overall width of said cov- 10 ered shunt being greater than the distance be- 15 tween the core and shell whereby to hold the shunt in position by and upon compression thereof.

3. A transformer including a substantially rec- 15 tangular magnetic shell, a core in the shell, primary and secondary windings embracing the core, means to hold the shell, core and windings with permanently defined spaces therebetween, a shunt in each space having laminations, and a mass of rubber covering and enclosing the shunts, the overall width of said covered shunts 20 being greater than the distance between the core and the shell, and the rubber mass being of a degree of resiliency and compressibility to hold the shunts in position by and under compression and to simultaneously clamp the laminations of the shunts together so as to hold the laminations 25 against vibration.
